UNITED STATES PATENT OFFICE.

HARVY BARRE CUNNINGHAM, OF ST. PAUL, MINNESOTA.

DEVICE FOR REWINDING FILMS.

1,195,785.

Specification of Letters Patent. Patented Aug. 22, 1916.

Application filed January 27, 1913. Serial No. 744,417.

To all whom it may concern:

Be it known that I, HARVY BARRE CUNNINGHAM, a citizen of the United States, residing at St. Paul, in the county of Ramsey and State of Minnesota, have invented new and useful Improvements in Devices for Rewinding Films, of which the following is a specification.

My invention relates to improvements in devices for re-winding moving picture films.

When a picture film is displayed and passed through a picture machine, it is unwound from one film reel and wound on to another. To use the film again it is, of course, necessary to re-wind it so that the pictures thereon will be shown in their proper order when again displayed. In the use of devices commonly employed in operating rooms for this purpose, the film, owing to breaks or defects therein, is frequently spilled from the unwinding reel and becomes tangled on the table or floor of the room. In this way, the film is often scratched or otherwise damaged and it also endangers the operator and building as a film so exposed is readily ignited by contact with the apparatus common in operating rooms.

It is my object to provide a simple, durable and efficient machine of this kind adapted to prevent such spilling and tangling and to re-wind a film from one reel to another and completely incase said film during such operation to prevent damage thereto and eliminate the danger accompanying present practice.

In the drawings, Figure 1 is a rear elevation of my improved device; Fig. 2 is a front elevation of the same with the casing door open; Fig. 3 is an enlarged horizontal central sectional view with the door closed and Fig. 4 is a detail sectional view illustrating the electrical switch mechanism and the latch for the door of the casing.

In the drawings, I have used the reference numerals 10 and 11 to designate the standards. The sheet-metal casing 12, having a door 13, pivoted on spring hinges 14 at the front thereof, is supported upon and secured to said standards. Said hinges are placed upon the lower edge of the door 13 and are of the ordinary type which balance when the door is open. The margins at the ends and top of the door are turned inward to form flanges 13^a and the edges of said flanges are turned over the rod 13^b to form a bead 13^c. These flanges overlap the ends

and top of the casing when the door is closed and form a tight joint between said door and casing. When the door is open a suitable working table is formed thereby and the flanges 13^a serve to retain loose articles and also prevent the springing of a film from a reel supported on said door. The standard 10 is formed with a bearing 15 and 60 the standard 11, with bearings 16 and 17. The drive shaft 18 is revolvably mounted in the bearing 15 of the standard 10, and the driven shaft 19, in the bearing 16 of the standard 11. These shafts protrude into 70 the casing 12, each being furnished with a collar 20 formed with a longitudinal perforation 21 in the rim thereof and supplied with a set screw 22. Each shaft is adapted to receive an ordinary film reel 23 and is 75 provided with an L pin 24, one end thereof being inserted in a transverse perforation 25 in said shaft, the other end being inserted in the longitudinal opening 21 of a collar 20. These pins are adapted to be engaged 80 by the notch 26 common on the ordinary film reel. The inner end of each shaft is formed with an annular groove 27 adapted to receive the yielding prongs 28 of a spring clip 29 which is placed over the end of the 85 shaft to retain a reel in position thereon. The outer end of the driving shaft 18 is supplied with a drive pulley 30 rigidly secured thereto, and a second drive pulley 31 adapted to turn loosely thereon or be secured to 90 said shaft by the set screw 32. The outer end of this shaft 18 is also provided with a stop pin 33 to prevent accidental removal of the drive pulley therefrom. The outer end of the driven shaft 19 is threaded to receive 95 the nut 34 and the lock nut 35 and a coiled spring 36 encircling the shaft is compressed between said lock nut 34 and the washer 37 which abuts against the bearing 16. The tension of said spring 36 may be adjusted 100 and fixed by the manipulation of the nuts 34 and 35 to prevent slack in the film and to retard the coasting of the driven reel.

The shaft 38, provided with a pulley 39 at one end, is revolvble within the bearing 105 17 of the standard 11 and is supplied at its other end with a handle 40 loosely and slidably mounted thereon. A clutch pin 41, extending transversely through said shaft, is adapted to be engaged by the notch 42 in 110 the hub 43 of said handle and rigidly connects the handle with the shaft when so engaged. The stop pin 44, at the end of said shaft 38, prevents accidental removal of the

handle 40 therefrom. The pulleys 30 and 31 on the driving shaft 18 are respectively connected by the belts 45 and 46 to the pulley 39 on the shaft 38 and to the pulley 47 on the motor 48, as illustrated in Fig. 1.

It is possible to normally rotate the reels only when said reels are completely housed. The door 13 of the casing 12 is arranged to fall into the path of the handle 40 and therefore 10 by prevent the rotation of the driving shaft 18. I have also provided a switch 49 for the motor circuit, which is opened and closed by the movements of the door 13. This switch consists of a pair of terminals 50 in 15 the switch housing 51 on the casing 12. The plunger 52, of insulating material, is slideable horizontally at one end in said casing and housing and at its other end in the bearing 53 of said casing. The coiled spring 20 54 is interposed between the casing 12 and the pin 55 in said shank and operates to normally disengage the contact head 56 of said plunger 52 from the terminals 50, thus opening the circuit. The end of the plunger 25 52 rests in the path of the door and when said door is closed, engages the same, thus causing the plunger to be moved and held in position closing the electric circuit to the motor. The spring catch 57 on the casing 30 12 is adapted to engage the bead 13^c of the door 13 and retain the same in closed position.

In use, a reel containing a film is mounted on the driven shaft 19 and secured thereto 35 by the clip 29. An empty reel is placed on the driving shaft 18 in a similar manner and the end of the film is secured to said reel. It is ordinarily desirable to operate the driving or winding reel by power from the 40 motor, such operation being possible only when the door 13 is closed. During such operation, the handle 40 is removed from engagement with the pin 41 and hangs loose on the shaft 38. It is sometimes, however, 45 desirable that the operator wind the film step by step when the door 13 is open in order that a damaged film may be intermittently stopped for repair. When this is done, the plunger 52 is successively manipulated 50 by the operator to connect the circuit to the motor and rotate the driving reel intermittently. The device may be operated continuously by the handle 40 when the door 13 is closed by unclutching the drive pulley 31 55 from the shaft 18 and moving the handle 40 to engage the pin 41 on the shaft 38. The handle may also be employed to move the film slowly and intermittently for close inspection or repair when the door 13 is open, 60 this movement being accomplished by successive partial turns of the shaft 38 by the handle 40, said handle being disconnected between such turns.

Having described my invention, what I claim as new and desire to protect by Letters 65 Patent, is:

1. In a device of the class described, the combination of a casing formed with an opening at one side thereof, a door for said opening, reel supports revoluble in said 70 casing, an electric motor in operative connection with one of said supports for turning the same, a source of current electrically connected with the motor and a device adapted to normally disconnect the motor 75 and source of current, said device being actuated by the door, when closed, to connect said motor and source of current.

2. In a device of the class described, the combination of a casing formed with an 80 opening at one side, a door for said opening, standards for said casing, reel supports in said casing revolubly mounted in said standards, a motor in operative connection with one of said supports for rotating the same, a 85 source of current electrically connected with said motor, and a switch mounted on the casing and operated by said door upon the opening and closing thereof to break and complete the motor circuit.

3. In a device of the class described, the combination of a casing formed with an opening at one side, a door for said opening, standards for said casing, reel supports in 90 said casing revolubly mounted in said standards, a motor in operative connection with one of said supports for rotating the same, a source of current electrically connected with said motor, a switch mounted on the casing and operated by the opening and 95 closing of the door to break and complete the motor circuit, and yielding means in operative connection with the other reel support for retarding its rotation.

4. In a device of the class described, the combination of a casing formed with an opening at one side, a door for said opening, standards for said casing, reel supports in 100 said casing revolubly mounted in said standards, mechanism in operative connection 105 with one of said supports for rotating the same by hand and by power, a source of current electrically connected with said motor, a switch mounted on the casing and operated by the opening and closing of the door 110 to break and complete the motor circuit, and adjustable means in operative connection with the other reel support for retarding its rotation.

In testimony whereof, I have signed my 120 name to this specification in the presence of two subscribing witnesses.

HARVEY BARRE CUNNINGHAM.
